UNITED STATES PATENT OFFICE.

EDWARD A. JOHNSTON, OF STERLING, ILLINOIS.

HARVESTER-BINDER.

No. 801,986.

Specification of Letters Patent.

Patented Oct. 17, 1905.

Application filed March 8, 1905. Serial No. 249,098.

To all whom it may concern:

Be it known that I, EDWARD A. JOHNSTON, a citizen of the United States, residing at Sterling, county of Whiteside, State of Illinois, have invented certain new and useful Improvements in Harvester-Binders; and I do hereby declare the following to be a full, clear, and exact description of the invention, such as will enable others skilled in the art to which it applies to make and use the same.

The invention relates to harvester-binders, and has particular reference to the devices that are located at the front and rear sides of the binder-deck at its upper end for receiving the grain as it comes from the elevator and directing and forwarding it in proper position and condition to the binding devices. In these machines it is desirable that the butt-adjuster at the forward side of the binder-deck should be adjustable fore and aft with the binder attachment and also that it should have a proper support and be adjustable independently of the binder. It is also desirable that the headboard at the rear end of the binder-deck should be capable of folding up and over upon the shield or covering-board, so as to permit free access into the space between the rollers at the upper end of the elevator, where the grain passes onto the binder-deck.

With these ends in view the invention consists in an improved means for supporting and adjusting the oscillating butt-adjuster and its guide-board and a novel arrangement for mounting the headboard, so that by a manipulation to be described later on it may be turned up and laid down flat on the metal shield, which extends from the upper part of the elevator over the upper end of the binder-deck.

The invention is illustrated in the accompanying drawings, in which—

Figure 1 is a fragment of a harvester-binder from the front side of the machine, showing the means for supporting and operating the butt-adjuster. Fig. 2 is a plan view of the same devices. Fig. 3 is an elevation of the fragment of the machine illustrated in Fig. 1 looking toward the rear side of the machine. Figs. 4 and 5 are detail views illustrating means for mounting the headboard; and Figs. 6 and 7 are perspective details of the rear upper corner of the elevator and binder-deck, showing the means for supporting the headboard and the manner of turning it up. Fig.

8 is an enlarged view, partly in section, showing the connection between the bracket *k* and the butt-board and its guide.

Referring to the views, *a* wherever occurring denotes the upper end of the elevator structure.

b indicates the binder deck or table, and *c* denotes the shield or covering-board which is secured to the elevator and extends for a short distance over the binder-deck, as best indicated in Figs. 3 and 6.

The binder mechanism or attachment is denoted at *d*. It forms no part of the present invention and may be of any desired construction. It is supported at its lower end in the usual manner, and the part *d'*, which overhangs the binder-deck, is supported by a radius bar or link *e*, which is pivotally connected to the binder at its outer end and similarly connected at *f* to an extension *g* of one of the supporting-standards at the front end of the elevator. The binder attachment is adjusted fore and aft in the usual way by any suitable devices, and the above-described link swings as the binder is adjusted, as indicated in dotted lines in Fig. 2, and steadies and supports the binder in its different positions.

The butt-adjuster is a board *h*, having ribs upon its rear face, as usual, and set edgewise along the front side of the binder-deck at its upper end. The board may be oscillated in any preferred manner; but as herein shown the power is taken from a crank *i* at the upper end of a diagonal shaft *j*, which drives the upper rollers of the elevator, as clearly illustrated in Fig. 1. The outer end of the oscillating board of the adjuster is supported from the overhead strap or radius-bar *e* by means of a downhanging bracket *k*, having at its lower end a horizontal shoe or foot *l*, that is curved on an arc struck from the upper pivot of the binder-supporting strap, so that the board may be adjusted independently of the binder in any of the positions of adjustment of the latter without interfering with the freedom of movement of the board or the crank and gearing which drives it. The outer end of the board *h* is connected to the bracket *k* by means of a link *m*, having its ends bent in opposite directions to form pivots, one of which is sleeved in a bearing *n*, formed on the bracket *k*, and the other of which is journaled in bearing on a plate *o*, attached to the forward side of the board *h*, so

that as the shaft *i* causes the upper end of the board to have a rotary motion the link *m* allows the lower end of the board to oscillate in a manner that is well understood in this 5 class of devices. The bracket *k* has, in addition to the curved foot-piece *l*, a downwardly and forwardly extending arm *p*, and to the forward end of this arm is attached by its upper end the guide-board *q*, which forms in 10 operation an extension of the oscillating board *h*. At its outer end the oscillating board *h* has a slide *s* mounted on it, whose upper and overturned edges clasp the horizontal edges of the curved foot *l* of the bracket, and this slide 15 constitutes the immediate means for supporting the oscillating board from the bracket *k*, as shown in Fig. 2, where it will be seen that the slide is also curved to the same radius as the shoe *l* and moved along the same into any 20 position desired.

The butt-board *h* and its guide *q* are adjusted into any desired position by means of a rod *r*, which extends to the top of the elevator, where it may be reached by the driver. 25 The forward end of the rod is pivotally connected to the slide *s* on the butt-board, and the rod being provided at its upper end with any of the usual adjustments for that purpose the butt-board may be shifted and set 30 into any position desired independently of the binder, and being supported as above described from the overhead strap or bar *e*, which supports the binder, it will also move with the binder as the latter is adjusted for 35 long or short grain.

The headboard is shown at *a'*, Fig. 3. It is a flat plate of sheet metal and is journaled on the downhanging end of an arm *b'*, that is supported by a casting *c*, secured to the rear 40 upper corner of the elevator. As best shown in Figs. 4, 5, and 6, this casting has a bracket with a squared bearing *d''*, and the horizontal arm of the rod *b'*, which carries the headboard, is supported in this bearing, so as to turn 45 therein when moved into a certain position and so also as to be held against turning when set in its normal position with the board extending along the rear edge of the binder-deck. The construction which enables the 50 rod to have this capability of adjustment is best shown in Fig. 4, where it will be seen that that portion of the rod nearest its bend is square, as shown at *e'*, so as to fit the squared opening in the bracket *d''*. The rod *b* extends some distance forward through the 55 bracket *d''* and is rounded beyond the squared part *e'*, as shown at *g'*, so that when pulled to the rear, as indicated in dotted lines in Fig. 5, it may be revolved in the bearing *d''* and 60 turned up into the position shown in dotted lines in Fig. 3 and in full lines in Fig. 7, when the headboard *h* will simply fold down over the top of the shield or covering-board *c*, that 65 extends from the elevator over the deck, as above described. The horizontal part of the

rod *b'* is encircled by a spring *h'*, which acts to keep the rod normally in a forward position with its squared part *e'* fitting the squared opening in the bracket *d''*, and the board *a'* is connected to the downhanging arm of the 70 rod *b'* by the usual spring *t'*. The construction being as thus described, it will be noted in respect of the headboard that it is not necessary to disconnect the board from its bearings in order to open fully the passage-way 75 at the upper rear corner of the elevator and binder-deck, but that free access may be had to the throatway between the elevator-rollers at this point by simply pulling the downhanging arm *b'* rearward and turning it outward 80 into the position shown in dotted lines in Fig. 3, when the board falls naturally into a horizontal position over and upon the shield *c*.

In respect of the butt-adjuster it is to be particularly noted that its outer end is supported from the overhead link, by means of which the weight of the upper parts of the binder attachment is carried from the elevator and also that both the oscillating board *h* and its tail-board or guide *q* have a wide range 90 of adjustment both with and independently of the binder.

Having thus described my invention, what I claim is—

1. In a harvester-binder, the combination of 95 the elevator, the binder, a supporting link or strap pivotally connected at opposite ends to said elevator and binder, and an oscillating butt-board adjustably supported by a downhanging bracket from the binder-supporting strap.

2. In a harvester-binder, the combination of 100 the elevator, the binder, a link or strap pivotally connected at opposite ends to said elevator and binder, a bracket depending from 105 said strap and having a foot or shoe at its lower end, and an oscillating butt-board connected to an operating-crank at its upper end and having a slide at its lower end running on the foot of the bracket, said foot being 110 curved on an arc from the upper pivot of the binder-supporting strap.

3. In a harvester-binder, the combination of 115 the elevator, the binder, a link or strap pivotally connected at opposite ends to said elevator and binder, a bracket *k* depending from said 120 strap and having a curved foot or shoe *l* at its lower end, and an oscillating butt-board having a guide-board and connected to an operating-crank at its upper end, and having a slide 125 *s* at its lower end running on the foot of the bracket, the bracket having an extension *p* to which the guide-board is fastened.

4. In a harvester-binder, the combination of 130 the elevator, the binder-deck, and a headboard secured to an arm that is journaled in a bearing transverse to the board so that the board may be swung up vertically.

5. In a harvester-binder, the combination of 135 the elevator, the binder-deck, a headboard, and

an angular arm having horizontal and down-hanging vertical parts, the horizontal part of which is journaled in a bearing so as to permit the board to be swung up vertically, the 5 board being hinged on the downhanging part of the arm so as to lie flat when raised vertically.

6. In a harvester-binder, the combination of the elevator, the binder-deck, a headboard, 10 and an angular arm having horizontal and vertical parts, the horizontal part of which is angular or square for a portion of its length and fits into a correspondingly-shaped bearing, another portion of said horizontal arm 15 being round and adapted to be slid into the bearing to permit the arm to turn therein so as to swing the headboard up.

7. In a harvester-binder, the combination of the elevator, the binder-deck, a casting *c'* 20 secured to the elevator and having an angular or square bearing *d''*, a headboard, a right-angled arm *b'* having vertical and horizontal parts, the horizontal part of which has an angular or squared portion *e'* fitting the bearing *d''*, and a spring for holding the angular portion of the horizontal arm in the bearing, 25 but permitting it to be withdrawn therefrom so as to allow the arm to turn in the bearing to raise the headboard up.

30 8. In a harvester-binder, the combination of an elevator, the binder, a supporting-link, pivotally connected at opposite ends to said elevator and binder, and a butt-adjuster, ad-

justably supported by the binder-supporting link.

35

9. In a harvester-binder, the combination of an elevator, the binder, a supporting link or strap pivotally connected at opposite ends to said elevator and binder, and an oscillating butt-board adjustably supported by the 40 binder-supporting strap.

10. In a harvester-binder, in combination, the binder-deck and grain-shield which form a grain passage-way, a headboard having two 45 relatively-transverse axes of movement, one of said axes being located above the grain passage-way.

11. In a harvester-binder, in combination, the binder-deck and grain-shield which form a grain passage-way, a headboard having a 50 relatively fixed and movable axis of movement, the fixed axis being located above the said grain passage-way.

12. In a harvester-binder, in combination, the binder-deck and grain-shield which form 55 a passage-way, a headboard having a relatively fixed and a movable axis of movement arranged transversely and intersecting with respect to each other, said fixed axis being located above the grain passage-way. 60

In testimony whereof I affix my signature in presence of two witnesses.
